UNITED STATES PATENT OFFICE

GEORGE W. BERNAUER, OF ST. CHARLES, MISSOURI

COMBINED CURTAIN, AWNING, AND SHADE

Application filed July 29, 1927. Serial No. 209,208.

This invention relates to a combined curtain, awning and shade, and an object is to provide means for utilizing a curtain as an awning and shade in connection with windows pivoted upon horizontal axes.

Another object of the invention is to provide a sheet of material for use as a curtain, awning and shade, in combination with a rotary tube or cylinder for supporting the same, gravity actuated means forming a weight in connection with the roller edge of the curtain, awning and shade for extending the same downwardly when the tube or cylinder is permitted to rotate, and means for securing the lower edge of the curtain, awning and shade around the outwardly extended edge of a pivotally supported window sash in a relationship to permit free circulation of air around the edges of the curtain, awning and shade through the window.

Another object of the invention is to provide improved means for rotating the supporting tube or cylinder to wind the curtain, awning and shade thereon and the device for holding said rotating means in any selected position to prevent turning of the tube or cylinder in either direction, so that the curtain, awning and shade will remain in its different adjustments.

Other objects will appear from the following description, reference being made to the drawings, in which

Fig. 1 is an inside view of my invention applied to a double window.

Fig. 2 is a vertical sectional view showing the device secured in position to function as a curtain, awning and shade.

Fig. 3 is an enlarged view showing details of the invention.

Fig. 4 is a vertical sectional view on the line 4-4 of Fig. 3.

Fig. 5 is a side elevation of one of the fixtures for supporting the end of the supporting tube or cylinder.

Fig. 6 is a side elevation of one of the intermediate fixtures.

Fig. 7 is an enlarged sectional view of the guide and holder for the actuating chain.

As shown, my invention is applied to a pair of adjacent windows, the same comprising a

tube or cylinder 1 rotatively supported in fixtures of novel construction, and having the curtain, awning and shade elements for the respective window connected therewith. In using the invention in connection with two or more windows, I provide a pair of end fixtures, each comprising a rod or wire shaped to form a ring 2 (Fig. 5) and a pair of angular arms 3 extending upwardly from the ring, and thence outwardly, one above the other, through the flange 4 of a metallic window frame, and being clamped in connection with the frame by nuts 5. The intermediate fixture comprises a wire or rod shaped to form a ring 6 and a pair of outwardly extending arms 7 passing through the intermediate portion of a metallic channel window frame member 8 and secured thereto by clamping nuts 9 in a relationship in which the rings 2 and 6 are in horizontal alinement. The tube or cylinder 1 is rotatively mounted in these fixtures and held from longitudinal movement in either direction by inwardly extended flanges 10 of the window frame structure.

The tube or cylinder 1 has a longitudinal slot 11. The upper edge of each combined curtain, awning and shade 12 extends through the slot 11 and is secured around a rod 13 within the tube or cylinder 1, which rod is of greater diameter than the width of the slot 11, so that it cannot pass through said slot. The lower end of each combined curtain, awning and shade is secured around a comparatively heavy rod 14, the weight of which is sufficient to hold the part 12 extended and to prevent the same from becoming crinkled. As a reinforcement and to prevent tearing of the material of the part 12, a strong thread 15 is wound around the material 12 near each end of the rod 14 and sewed through the folded material, as clearly shown in Fig. 3.

A sprocket wheel 16 is attached to the tube or cylinder 1 adjacent to the middle fixture 6 and opposite the middle window frame part 8. An endless sprocket chain 17 is supported on the sprocket wheel 16 and extends downwardly to a point near the lower end of the window, one part of the sprocket chain being within the channel of the frame member 8

and the other part being toward the inside of the roll for convenient manual engagement. This sprocket chain passes through a guide block 18 secured to the frame member 5 near the lower end of the latter. For use in connection with this guide block to hold the chain from movement, I provide a latch element comprising an insertable and withdrawable pin 19 which may be passed 10 through the block and across the hole through which the chain passes and between adjacent sprocket chain link ends 20 of the familiar type.

I secure to each of the rods 14 near its 15 middle a cord 21.

This invention is specially designed and adapted for use in connection with the type of windows shown which are extensively used in manufacturing establishments and 20 other business structures. Each of these windows comprises an intermediate window portion 22 mounted in connection with the window frames on horizontal pivots 23 intermediate to the upper and lower edges of 25 said window sections. These window sections turn on their horizontal axes from closed to open position and vice versa. Each window section is usually provided at one end with a pivoted latch arm 24 having notches 30 25 arranged to engage the upper sash member 26 of the adjacent lower window section 27, so as to support and hold the window sections 22 open.

When it is desired to use the invention to 35 provide a combined curtain, awning and shade, the adjacent window section 22 is opened to the proper extent by swinging the upper edge thereof inwardly and the lower edge outwardly. The latch 19 being 40 clamped, the chain 17 is then operated to rotate the tube or cylinder 1 to extend the curtain, awning and shade element 12 downwardly, placing the lower edge thereof outwardly beyond the outer side of the upper 45 edge of the window section 12 and such operation is continued until the lower edge of the curtain, awning and shade passes below the lower edge of said window section 12. Then the window section 12 is secured in the 50 position desired by latching the arm 14 on the window sash member 26 and the lower end of the curtain, awning and shade is drawn inwardly against and under the lower edge of the window section 22 (Fig. 2) and the cord 55 21 is secured to a fastener 28 on the sash 26. Thus, it will be seen that the part 12 functions as a combined curtain, awning and shade and is securely held in the adjustment in which it is placed. Accidental disarrangement of the parts is prevented by replacing the latch pin 19 in the block 18.

It will be understood that, when these combined curtains, awnings and shades are used in series, as shown, any one or more of them 60 may be adjusted as described, as it is unnec-

essary to open all of the corresponding windows 22. Thus, one or more of the devices may be used as a combined curtain, awning and shade, while the remainder may be used as curtains without being extended to the outside.

The invention is capable of every variation within the range of mechanical equivalents without departure from the nature and principle thereof.

I do not restrict myself unessentially, but what I claim and desire to secure by Letters Patent is:—

1. A shade comprising a rotary support mounted near the upper end of a window frame, a sheet of shade material attached to said support, a sprocket wheel attached to said support, a chain passing over and extending downwardly from said sprocket wheel, knobs on said chain, a guide through which said chain extends below said sprocket wheel, and a removable latch element passing through said guide transversely of said chain between said knobs and holding said chain from movement.

2. A shade comprising a rotary support mounted near the upper end and at the inner side of a window frame, a sheet of pliable material attached to said support and being of a width such that it may be extended at full width outwardly through the window frame, a window sash pivoted in said frame, and means for holding said sheet extended downwardly and outwardly at full width in engagement with the lower end of said window sash.

3. A shade comprising a rotary cylindrical support mounted near the upper end and at the inner side of a window frame at the inside of the window, a sheet of shade material attached to said support and being of a width such that it may be extended at full width outwardly through the window frame, means for rotating said support to roll and unroll said sheet, a window pivoted for turning movements on a horizontal axis to position in which one end is at full width extended outwardly, and means for holding said sheet against the outwardly extended end of said window.

4. The combination with a window frame, a window in the upper portion of said frame, another window pivoted in said frame below said first named window for turning movements on a horizontal axis to position in which one end thereof is extended outwardly, and means for holding said second window in the position aforesaid, of a sheet of shade material having one end supported near the upper end of said frame at the inner side of said first window, and means for holding said shade in position in which it extends below said first window and downwardly and outwardly against the outwardly extended end of said second window.

5. The combination with a window frame, a window in the upper portion of said frame, another window pivoted in said frame below said first named window for turning movements on a horizontal axis to position in which one end thereof is extended outwardly, and means for holding said second window in the position aforesaid, of a sheet of shade material having one end supported near the upper end of said frame at the inner side of said first window, means for holding said shade in position in which it extends below said first window and downwardly and outwardly against the outwardly extended end of said second window, and means for rolling and unrolling said sheet. 10
- 15 5 70 75
6. The combination with a window frame, a window in the upper portion of said frame, another window pivoted in said frame below said first named window for turning movements on a horizontal axis to position in which one end thereof is extended outwardly, and means for holding said second window in the position aforesaid, of a sheet of shade material having one end supported near the upper end of said frame at the inner side of said first window, means for holding said shade in position in which it extends below said first window and downwardly and outwardly against the outwardly extended end of said second window, and means for rolling and unrolling said sheet, and a device for preventing accidental operation of said means. 20 25 30 35 40 45 50 55 60 65 70 75 80 85 85 90 95 100 105 110 115 120 125 130
7. In a window of the character described, a frame, window elements in said frame, a roller at the inner side of said window elements, a sheet of shade material attached to said roller, means for operating said roller to roll and unroll said sheet, and means cooperating with said sheet for holding said sheet extended at full width downwardly and outwardly through said frame beyond the outer sides of said window elements. 10 15 20 25 30 35 40 45 50 55 60 65 70 75 80 85 90 95 100 105 110 115 120 125 130
8. In a window of the character described, a frame, window elements in said frame, a roller at the inner side of said window elements, a sheet of shade material attached to said roller, means for operating said roller to roll and unroll said sheet, means cooperating with said sheet for holding said sheet extended at full width downwardly and outwardly through said frame beyond the outer sides of said window elements, and a device for preventing rotation of said roller. 10 15 20 25 30 35 40 45 50 55 60 65 70 75 80 85 90 95 100 105 110 115 120 125 130
9. A window opening having a sash intermediate of its upper and lower ends for turning movements from closed position to position in which the lower end is extended outwardly, a sheet of shade material having one end supported near the upper end and at the side of said window opening and adapted to be extended outwardly and downwardly against the outer end of said sash when said sash has its lower ends positioned outwardly 10 15 20 25 30 35 40 45 50 55 60 65 70 75 80 85 90 95 100 105 110 115 120 125 130
